UNITED STATES PATENT OFFICE

WILLIAM G. KEITH, OF CHICAGO, ILLINOIS, ASSIGNOR TO WELSEACH TRAFFIC SIGNAL COMPANY, OF PHILADELPHIA, PENNSYLVANIA, A CORPORATION OF DELAWARE

ELECTRICAL FLASHER

Application filed June 20, 1927. Serial No. 200,168.

This invention relates to electrical flashers and has special reference to electromagnetically operated flashers for controlling electric signal devices, electric signs and the like.

More particularly, this invention has reference to an electrical flasher wherein a pair of fluid contact making-and-breaking members are operated by an electromagnet, one of said contact making-and-breaking members being adapted to control an electrical circuit for energizing said electromagnet and the other of said contact making-and-breaking members being adapted to control an electrical circuit for operating the load.

Inasmuch as devices of the character indicated above are continuous in action, it is desirable that such devices be simple in construction, simple in operation and that they require a minimum amount of electrical current for their operation. Moreover, it is particularly desirable to provide a construction which is capable of opening and closing an electrical circuit indefinitely without substantial deterioration or disintegration of the contact making-and-breaking members or of the operating mechanism generally.

The present invention, which conforms to the foregoing requisites, comprises a pendulum pivotally connected to a support, the pendulum having a pair of electrical switches preferably of the tilttable fluid contact making-and-breaking types mounted thereon and operated by an electromagnet. One of the electrical switches controls the operation of the electromagnet while the other of the electrical switches is connected to a lamp or other suitable load which latter is controlled thereby.

One of the objects of this invention is to provide an electrical flasher of the type referred to above which will be simple and efficient in operation and durable in construction.

Another object of this invention is to provide an electrical flasher as indicated above

which, by means of an unbalanced magnetic field, will be self-starting and will eliminate the necessity of counterbalancing means for the armature thereby reducing the amount of electrical energy required for its operation.

A further object of this invention is to provide an electrical flasher as described above which is controlled by a pair of preferably coordinated electrical switches operating in separate electrical circuits whereby the lamp circuit may be fed from a higher potential circuit than that of the battery, and whereby a defective condition in the lamp circuit will not stop the operation of the flasher.

It is also the object of this invention to provide an electrical flasher of the type as noted above in which the length of flash period may be conveniently regulated.

A still further object of this invention is to provide an electrical flasher of the before mentioned design in which the number of flashes per minute may be readily controlled.

Further objects and advantages of this invention will be apparent from the following description and accompanying drawings and for a better understanding of the nature, scope and characteristic features of this invention, reference may now be had to the following description and the accompanying drawings in which drawings:

Figure 1 is a side elevational view of an electrical device in which the invention may be embodied;

Fig. 2 is a side elevational view of the mechanism of the electrical flasher showing the casing thereof in section;

Fig. 3 is a rear elevational view of a portion of the mechanism of the electrical flasher;

Fig. 4 is a plan sectional view taken on the line 4—4 of Fig. 2;

Fig. 5 is a wiring diagram of the electrical circuit embodied in this invention as illustrated by the previously described figures.

Referring now to the drawings and par-

ticularly to Figs. 1 to 4, inclusive, therein, the present invention is shown as embodied in a signal apparatus 10 for illustrative purposes only since this device may be employed for operating electrical signs, apparatus for spectacular illumination of all kinds and all devices and apparatus wherein a periodic make-and-break of an electrical circuit is employed.

10 The signal device 10 in this instance is used as a warning, particularly for motorists and is placed at the end of the street, a turn in the road, railroad crossings, intersections in streets, etc. This device comprises a signal head in which is positioned an electrical lamp which is disposed centrally of the lens 12, a standard 13 for said signal head mounted on a container 14, an electrical flasher 15 centrally located in said container and for operating said lamp, and batteries 16 in the lower portion of said container for operating said electric flasher and, in this particular instance, for lighting said electric lamp. However, as will be hereinafter more fully described, these batteries may be employed for operating the electrical circuit of the electro-magnetically operated means only as it may be desirable to operate the lamp from a source of supply which is of a higher potential than that of the batteries.

15 The electrical flasher 15 comprises a metal base 17, having a pair of vertically extending supports 18 suitably secured thereto. These supports are secured together at a point 20 near the upper ends thereof by means of a U-shaped bracket member 19 which is preferably formed integrally with the supports. The extreme upper ends of said supports are provided with horizontally extending arms 25 upon which latter members is mounted an insulating plate 21 for carrying a plurality of terminals.

20 An electromagnet 22 substantially of the horse shoe type is disposed on the U-shaped bracket 19 and comprises a preferably U-shaped soft iron core around which a coil of wire 23 is wound and insulated therefrom. The U-shaped core portion of the electromagnet is preferably inverted and has one of its arm members 24 secured to the bracket 19 by means of a screw 25, the surface of the bracket 25 coating with the arm 24 being slightly inclined to permit of a slightly tilted position of the electromagnet 23 and the arm 25 26 of the electromagnet having a substantially parallel relation with the arm 24. In other words, this construction provides that the magnetic field be asymmetrical with respect to the armature and the supporting structure 30 so as to produce an unbalanced magnetic field.

25 In order to periodically light the lamps of the signal device, a pair of tiltable fluid contact making-and-breaking members 27 and 28 are disposed in supporting members 29 and 30, respectively, each of which latter mem-

bers comprises a plate which is pivotally secured at one end thereof to a plate 31 mounted on an armature 32. A pair of arm members preferably integrally formed with the plate of its supporting member extend upwardly to form clips which engage the contact making-and-breaking members and hold the same in a fixed position therewith.

30 The armature 32 comprises a bar of soft iron of a size to conform to the core portion of the electromagnet 22 and is disposed between the ends of the arm members 24 and 26. A sufficient amount of clearance is allowed between the ends of the armature and the arms 24 and 26 so as to permit of an oscillation of the armature therebetween. The armature is mounted on a shaft 33 which extends between the upright supports 18 and is pivotally mounted thereto as by means of a reduced portion 34 on each end of said shaft 33 engaging an aperture in a screw member 35 extending through said upright supports 18. The screw members 35 are held in a fixed relation with the supports 18 by means of lock nuts 36.

35 The contact making-and-breaking members 27 and 28 are identical in structure and a description of one will therefore cover the structure of the other. The contactor 27 comprises an elongated hermetically sealed container having a pair of spaced cooperating electrodes disposed therein and at one end thereof, the electrodes being bridged by means of a compact and coherent body of a current conducting fluid such as mercury to permit of an electrical circuit to be completed therethrough. These tubes are adapted to be tilted in a desired direction whereby the mercury will be caused either to bridge or to flow away from the electrodes thereby making-and-breaking the electrical circuit therethrough.

40 A downwardly extending pendulum 37 is secured to the underneath side of the armature 32, the pendulum being disposed preferably in axial alignment with the horizontally extending shaft 33. The lower end of the pendulum 37 is provided with screw threads for receiving in threaded engagement therewith a weighted member 38. For shipping purposes, a screw 39 is extended through the base 17 and into the screw threaded aperture of the weighted member 38 whereby the pendulum is held in a substantially rigid position. When it is desired to operate the electrical flasher, the screw member 39 is disengaged from the weighted member 38 permitting the pendulum to swing freely. By means of adjustably mounting the weighted member 38 on the pendulum rod 37, the number of flashes obtained in the electrical flasher can be definitely determined whereby a positive periodicity is obtained therein.

45 By reason of the shaft 33 being located centrally of the armature 32 and by reason of the pendulum rod 37 being in axial align- 130

ment with the shaft 33, the armature 32 is normally held in a substantially horizontal position. As hereinbefore stated, the electromagnet is slightly tilted so as to obtain an unbalanced magnetic field. The pole of the arm 26 is in close proximity to one end of the armature 32, while the pole of the other arm 24 of the electromagnet extends a relatively greater distance below the other end of the armature 32, therefore when the coil of the electromagnet is energized, the arm 26 will be the operating pole to actuate the armature and the opposite pole of the magnet will be less effective.

In the operation of the electrical flasher thus far described when the electromagnet 22 is energized, the magnetic lines of force thread through the armature 32 thereby attracting one end of the armature to rotate the latter about its axis 33 as the armature seeks a position such that the maximum magnetic force may pass directly therethrough. The contactor tubes 27 and 28, being fixedly mounted on the armature 32, are tilted to a position such that the current conducting fluid contained therein flows away from the electrodes positioned at one end of the tubes to break an electrical circuit which normally exists therethrough. As one of the contactor tubes controls the electrical circuit through the electromagnet 22, this circuit opening causes the electromagnet to become deenergized thereby permitting the armature 32 to seek its normal horizontal position, the pendulum 37 and the weighted member 38 acting to return the armature to this position. It will be noted in the operation of the electromagnet that the arm 26 thereof is the operating pole to effect the raising of the end of the armature in close proximity thereto. The opposite pole of the magnet or the arm 24 is less effective than the first mentioned pole being somewhat below the axis of oscillation and acts more or less as a damper or buffer against too rapid oscillation.

In order to regulate the length of flash period, or that period of time at which the lamps or load are in a closed circuit position, a screw member 40 is threadedly engaged in the armature 32 and extends upwardly therethrough to abut the lower edge of the free end of each of the contactor tube supporting members. Should the screw members 40 extend a greater distance through the armature 32 than that shown in the drawings, the current conducting fluid in the container would flow away from the electrodes after but a slight oscillation of the armature 32 whereby a small flash period is obtained; whereas, should the screw member 40 recede from the position shown in the drawings, a greater rotation of the armature 32 would be required in order to permit the current conducting fluid to flow away from the electrodes where-

by a substantially great flash period is obtained. In the former, the current conducting fluid will be in contact with the electrodes but a minimum length of time; whereas, in the latter the current conducting fluid will be in contact with the electrodes for a maximum period of time.

In order to permit a free movement of the pivotal members, flexible connections are provided for the tiltable contactor tubes. One of the electrodes in the contactor 28 is secured to one end of a bracket 41 secured to and insulated from the shaft 33. One end of a coil spring conducting element 42 is connected to the other end of the bracket 41, the other end of the conducting element being secured to an arm 43^a of a terminal 43 insulated from and secured to the upright supporting member 18. The terminal 43 is in turn connected to one end of the coil 23 of the electromagnet, the other end of the coil 23 being connected to the terminal 44 which is mounted on the insulating plate 21.

The other electrode in the contactor 28 is connected to one of the electrodes in the contactor 27, this latter electrode being in turn connected to one end of a bracket 45 insulated from and disposed on the shaft 33. One end of a second coil spring conducting element 46 is secured to the other end of the bracket 45, the other end of the conducting element being connected to an arm 47^a extending from a terminal 47 mounted on the upright standard 18. This latter terminal 47 is connected to a terminal 48 mounted on the insulating base 21. The remaining electrode in the contactor 27 is connected to another coil spring conducting element 49, one end of said conducting element being secured to a bracket 50 to which latter the last mentioned electrode is suitably connected. The other end of the conducting element 49 is secured to an arm 51^a extending from a terminal 51, the latter terminal being connected to a terminal 52 mounted on the insulating base 21.

In order to more thoroughly understand the aforementioned electrical connections, reference may now be had to the wiring diagram of Fig. 5 wherein one electrode of the contactor 28 is connected through the coil 23 to the terminal 44. The other electrode of the contactor 28 is connected to one of the electrodes in the contactor 27 and thence to the terminal 52. The remaining electrode in the contactor 27 is connected to the terminal 48. The batteries 16 are connected between the terminals 44 and 52, while the lamp 53 contained in the housing 11 of the signal flasher is connected between the terminals 44 and 48.

When the contactors 27 and 28 are in a tilted position such that an electrical circuit exists therethrough, an electrical circuit is obtained from one side of the battery through

the terminal 44, the coil 23, the contactor 28 to the other side of the battery through the terminal 52, while another electrical circuit is obtained from one side of the battery through the lamp 53, the terminal 48, the contactor 27 to the other side of the battery through the terminal 52.

When no electrical energy is obtained through the electric flasher, it is preferable to permit the pendulum to hold the armature in a position such that a closed circuit exists through the contactors 27 and 28 in order that the mechanism of the electric flasher be self-starting when a supply of electrical energy is fed thereto. After the electrical current is supplied to the device, the electro-magnet 22 is energized to actuate the armature 32 and the lamp is energized to light the electrical flasher. However, it may be desirable to so arrange the electrodes in the ends of the contactor tubes 27 and 28 so that when the electrical flasher is at rest, as previously described, the contactor controlling the electromagnet occupies a closed circuit position while the contactor controlling the lamp or other load is in an open circuit position. In this manner, the electric flasher may be said to be self-starting as in the previously described construction.

While but a single embodiment of this invention is herein shown and described, it is to be understood that the device is not to be limited to that specific structure, since various modifications may be apparent to those skilled in the art without departing from the spirit and scope of this invention, and therefore, the latter is to be limited by the scope of the appended claims and the prior art.

I claim:

1. In a device of the character described, a support, an armature pivotally mounted thereon, a plurality of fluid contact making-and-breaking members adjustably mounted independently of each other on said armature, a pendulum for normally holding said armature in one position, and a substantially U-shaped electromagnet for actuating said armature into a second position, said armature being disposed between the arms of said electromagnet, said electromagnet being controlled by one of said fluid contact making-and-breaking members.

2. In a device of the character described, a support, an armature pivotally mounted thereon, a plurality of fluid contact making-and-breaking members mounted on said armature, means for normally holding said armature in one position, and an electromagnet asymmetrically disposed relative to and for actuating said armature into a second position, said electromagnet being controlled by one of said contact making-and-breaking members.

3. In a device of the character described, a support, an armature pivotally mounted

thereon, a tiltable switch mounted on said armature and actuated thereby, a pendulum extending downwardly from and secured to said armature for normally holding said armature in a substantially horizontal position, and an electromagnet normally asymmetrically disposed relative to said armature and for actuating said armature into a second position, said electromagnet being controlled by said tiltable switch.

4. In a device of the character described, a support, a substantially U-shaped electromagnet fixed to said support and disposed asymmetrically thereto, an armature pivotally mounted between the poles of said U-shaped electromagnet and actuated thereby, and switching means mounted on said armature for controlling electrical circuits, one of said electrical circuits controlling said electromagnet.

5. In a device of the character described, a support, an electromagnet having the pole members disposed asymmetrically relative to said support, an armature pivotally mounted between and influenced by said pole members, one of said pole members being normally disposed a slight distance above one end of said armature and the other of said pole members being disposed a comparatively greater distance below the other end of said armature, and switching means mounted on said armature for controlling electrical circuits, one of said electrical circuits controlling said electromagnet.

6. In a device of the character described, a support, an armature pivotally mounted thereon, a plurality of fluid contact making-and-breaking members pivotally mounted on said armature, means for adjusting the degree of tilt of said contact making-and-breaking members relative to said armature, and magnetic means for influencing said armature and controlled by one of said contact making-and-breaking members.

7. In an electric flasher, a support, an armature pivotally mounted thereon, a plurality of fluid contact making-and-breaking members pivotally mounted on said armature for controlling electrical circuits, means for adjusting the degree of tilt of said contact making-and-breaking members to control the length of flash period in said electric flasher, means for actuating said armature controlled by one of said electrical circuits, and a pendulum extending downwardly from said armature to control the number of flashes over a given period of time.

8. In an electric flasher, a support, an armature pivotally mounted thereon, a plurality of fluid contact making-and-breaking members pivotally mounted on said armature for controlling electrical circuits, an adjusting screw for engagement with each of said contact making-and-breaking members for regulating the degree of tilt thereof with re-

spect to said armature to control the length of flash period in said electric flasher, an electromagnet disposed asymmetrically with said support and said armature and controlled by one of said electrical circuits for influencing said armature, and a pendulum extending downwardly from said armature to predetermine the number of flashes over a given period of time.

10 In witness whereof, I have hereunto subscribed my name.

WILLIAM G. KEITH.
